[57] CLAIM

The ornamental design for a Christmas tree shaped pasta, as shown and described.

DESCRIPTION

FIG. 1 is a top plan view of a Christmas tree shaped pasta piece our new design, the undisclosed bottom being a mirror image;

FIG. 2 is a side view thereof, taken from the left-hand side of FIG. 1, the opposite side view being identical thereto;

FIG. 3 is a front view thereof; and,

FIG. 4 is a rear view thereof.
